United States Patent Office

Des. 185,408
Patented June 2, 1959

185,408

CARD HOLDING CLIP

Jack Zimmerman, New York, N.Y.

Application January 24, 1958, Serial No. 49,396

Term of patent 14 years

(Cl. D17—3)

FIG. 1.

FIG. 2.

I claim:

The ornamental design for a card holding clip, substantially as shown.
